RAILWAY SIGNAL TORPEDO

Filed Sept. 22, 1925

UNITED STATES PATENT OFFICE.

FRANK DUTCHER, OF VERSAILLES, PENNSYLVANIA, ASSIGNOR TO STANDARD RAILWAY FUSEE CORPORATION, OF BOSTON, MASSACHUSETTS, A CORPORATION OF NEW YORK.

RAILWAY SIGNAL TORPEDO.

Application filed September 22, 1925. Serial No. 57,843.

My invention relates to certain improvements in torpedoes, of the type in which the tablet is wrapped within an enclosing sheet of paper, and secured to the means 5 by which the torpedo is attached to a railway rail.

The object of my invention is to so wrap a tablet that the seams of the paper-enclosure will be completely covered, so that when 10 water-proofing cement is applied, the tablet will be completely protected from moisture.

In the accompanying drawings:

Fig. 1 is a perspective view of my improved railway track torpedo;

Fig. 2 is a view showing the sheet of wrapping paper with the tablet in position to be wrapped;

Fig. 3 is a view showing the torpedo wrapped, with the sheet of paper, covering 20 the entire upper surface, without seams;

Fig. 4 is an inverted perspective view of the partly-formed torpedo illustrated in Fig. 3, showing the seam on the underside;

Fig. 5 is a perspective view, showing the 25 reinforcing strip of paper placed in position to be folded;

Fig. 6 is a perspective view, showing the reinforcing strip folded under the wrapper; and

Fig. 7 is an inverted perspective view, 30 showing the folds of the reinforcing strip secured in position.

The explosive tablet 1 is preferably formed as shown in Fig. 2. The wrapper 2 is preferably made of a sheet of paper in which asphaltum, or other water-proofing material, is rolled between two plies of the paper, making the sheet water-proof. This paper is folded over the tablet, as indicated by the dotted lines, the portion 3 of the sheet of paper extending entirely over the upper surface of the tablet, as indicated in Fig. 3, while the end 5 extends under the

tablet, as shown in Fig. 4, the seam, therefore, being on the underside of the tablet. 45

A reinforcing strip 7 is preferably secured to the underside of the folded sheet, as indicated in Fig. 5, and the ends 6 of the folded sheet are turned under this reinforcing strip, and preferably secured thereto by cement. 50 Then the ends of this reinforcing strip are folded under the folded portion 6 of the main enclosure, as shown in Fig. 6, and the ends are cemented as shown in Fig. 7. The torpedo is then covered with a water-proofing cement, which closes all openings, so that the tablet is completely protected from moisture. 55

A retaining strip 8 of pliable metal, when used, is placed in position on the torpedo at 60 the same time that the reinforcing strip is applied, as shown in Fig. 5. The reinforcing strip and ends 6 produce an extra heavy base which will be impossible to tear under ordinary conditions. This gives a substantial support for the torpedo-tablet. 65

It will be understood that other means of securing the torpedo to the rail may be used in place of the pliable metal strip, without departing from the essential features of my 70 invention.

I claim:

The combination in a railway signal torpedo, of an explosive tablet; a rectangular wrapper which is folded over the tablet in 75 such manner that there will be no seam on the upper surface of the torpedo, the seam being located under the torpedo; a reinforcing strip extending at right angles to the folded paper; and fastening means extending parallel with said reinforcing strip, the side extensions of the folded wrapper being folded under the fastening means, and the ends of the reinforcing strip being folded under the folds of the wrapper. 80

FRANK DUTCHER.
